UNITED STATES PATENT OFFICE

FRED RING, OF NEW YORK, N. Y., ASSIGNOR TO DICTOGRAPH PRODUCTS CO., INC., OF NEW YORK, N. Y., A CORPORATION OF DELAWARE

WOMAN'S UNDERGARMENT

Application filed September 25, 1931. Serial No. 565,055.

This invention relates to a woman's undergarment and more particularly to such a garment adapted to support various units of a telephone device adapted for the aid of persons afflicted with defective hearing, and has for a general object the provision of such a garment adapted to support the transmitter, the battery and the tone control unit of such a device in a manner to insure a maximum of comfort to the user while attaining a desired concealment of these units and an efficient arrangement of the units such that they give a maximum of efficiency in use and to provide easy access thereto for desired adjustments. A more specific object of the invention is the provision of such an undergarment having a front provided with pockets to receive the transmitter, the battery and the tone control unit of a telephone device for the aid of persons afflicted with defective hearing and electrical conductor passages between these pockets to allow ready electrical connection between these units and a receiver unit, the pockets being arranged to insure a maximum of comfort to the user, the transmitter pocket being arranged in a position to insure efficient reception of sound waves and the tone control unit receiving pocket being arranged to insure easy access to the latter unit for adjustment thereof while the device is in use, insuring a maximum of efficiency in use and a desired concealment of the units and of their electrical conductors.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description

taken in connection with the accompanying drawing, in which:

Fig. 1 is a plan view of the front of an undergarment made in accordance with the present invention fitted with the units of a telephone device.

Prior to the present invention, telephone devices adapted for the aid of persons afflicted with defective hearing have been commonly supported on the outer clothing of the user in a variety of positions by a variety of means, the transmitter being usually exposed to view and being mounted by a suitable clip or pin, the battery and tone control units being disposed in pockets or supported by pins or clips. Such mounts have left exposed to view one or more of these units and the electrical conductors between these units and have been the source of an additional annoyance due to the fact that the weight of the units distorts the shape and renders unsightly the fit of the outer garments of the user. These undesirable features are a greater source of annoyance to women than they are to men since women's outer garments are less adapted for concealment of such objects and are formed from much less sturdy materials than are men's garments. In accordance with the present invention, a woman's undergarment is provided which eliminates the above difficulties and insures more efficient mounts and placements of the units of such a telephone device.

Referring to the drawing, an undergarment 2 having a front 3 supported by the usual shoulder strap supports 4, 4, is provided with a central pocket 5, preferably open at the top 6 and of a dimension such that a transmitter 7 can be received and supported therein. A pocket 8 is formed in the front of the undergarment, preferably to one side adjacent the waist-line thereof, preferably open at one end 9 to receive a battery 10. The pocket 5 is provided with an opening 11, preferably in the bottom thereof, which com-

municates with a passage 12 terminating at the open end 9 of the pocket 8 to receive the electrical conductors 13, forming electrical connection between the transmitter 7 and the 5 battery 10.

Adjacent one strap support 4 a pocket 14, preferably open at 15, is provided for the reception of the tone control unit 16 and an opening 17 is provided in one side of this 10 pocket to allow the passage of electrical conductors 18 between the tone control unit 16 and the usual receiver 19. The electrical conductors 20, which provide for electrical connection between the tone control unit 16 and 15 the battery 10 and transmitter 7, are preferably disposed in the pocket 5 leading therefrom into the pocket 14 through the open ends 6 and 15 of the pockets 5 and 14, respectively.

These pockets are preferably formed by 20 securing pieces of material to the under side of the garment in any suitable manner, such as, for example, by means of stitching, the opening into the battery pocket 8 being preferably formed by severing the material of 25 the garment along the line 9 to allow ready removal of the battery unit from the outside of the garment, as is possible with the transmitter 7 and tone control unit 16, since these pockets are preferably formed with openings 30 6 and 15 along the edges of the garment.

The position of the transmitter receiving pocket 5 not only insures a maximum efficiency in the reception of sound waves, but in addition provides for a secure amount 35 thereof in a position to insure a maximum of comfort to the user. Since the materials from which are made articles of wearing apparel for women are relatively very thin, no substantial impediment to the passage of sound 40 waves to the interior of the transmitter is experienced when the transmitter is so mounted. Placement of the battery 10 at the waistline, preferably at one side of the front of the garment and the tone control unit 16 at the 45 top of the garment adjacent one strap support 4, insures maximum comfort to the user and ready access to the tone control unit for adjustment thereof without materially disturbing the outer garments while the device 50 is in use.

It will thus be seen that the undergarment of the present invention efficiently attains the objects set forth above in an admirable manner, and that such a garment can be cheaply 55 and readily produced which provides a unitary mount for the transmitter, the battery and the tone control unit of the type of telephone device depicted, and constitutes in addition a commonly used article of apparel, 60 which when fitted with the units of such a device allows a ready and simple mount thereof on the person of the user in concealed positions.

Since certain changes may be made in the 65 above article and different embodiments of

the invention could be made without departing from the scope thereof, it is intended that all matter contained in the above description or shown in the accompanying drawing shall be interpreted as illustrative and not in a 70 limiting sense.

It is also to be understood that the following claims are intended to cover all of the generic and specific features of the invention herein described, and all statements of the 75 scope of the invention which, as a matter of language, might be said to fall therebetween.

Having described my invention, what I claim as new and desire to secure by Letters Patent, is:

1. A woman's undergarment comprising a front adapted to cover the chest of a wearer having two layers of material in the central portion, a relatively large article supporting pocket positioned centrally on said front within the region to be disposed adjacent the hollow of the chest formed by stitching together the two above mentioned layers of material, a second article supporting pocket positioned to one side on said front below the 80 region adapted to cover the fullness of the chest and formed by stitching together the two layers of material, a passage formed between said pockets by the two layers of material, and a third relatively small article supporting pocket disposed on said front adjacent the shoulder support above the last mentioned region and formed by stitching together the two layers of material. 85

2. A woman's undergarment comprising a 90 front formed from at least two layers of material except in the regions to be disposed adjacent the fullness of the chest, a substantially tapered shoulder strap anchoring portion adjacent each of the mentioned regions 95 formed from the two layers of material, a relatively large, centrally positioned, article supporting pocket on said front within the region adapted to cover the hollow of the chest and formed by stitching together portions of the two layers of material, a second article supporting pocket positioned on said front to one side and below the region adapted to cover the fullness of the chest and formed by stitching together portions of the 100 two layers of material with an opening thereinto through the outer layer of material, a passage formed between said pockets by the two layers of material and the deletion of a few stitches in the bottom of said central pocket and in one side of said pocket, and a third relatively small article supporting pocket formed on said front by stitching together the two layers of material of one of 105 said shoulder strap anchoring portions along the bottom and one side thereof, said third pocket having an opening adjacent the inner side thereof and being provided with a 110 passage adjacent the outer side thereof by the deletion of a few stitches. 115

120

125

130

135

3. A woman's undergarment comprising a body portion including a front adapted to cover the chest of a wearer, an article supporting pocket positioned centrally on said front within the region to be disposed adjacent the hollow of the chest, a second article supporting pocket positioned to one side on said body portion and below the region adapted to cover the fullness of the chest, a third article supporting pocket positioned to one side on said body portion outside the region adapted to cover the fullness of the chest, and passages in said body portion between said pockets.

15 In testimony whereof I affix my signature.
FRED KING.
